D. J. WALLACE.
SAFETY GAS BURNER.
APPLICATION FILED NOV. 29, 1913.

Patented Oct. 6, 1914.

UNITED STATES PATENT OFFICE.

DAVID J. WALLACE, OF THE UNITED STATES NAVY.

SAFETY GAS-BURNER.

1,113,076.

Specification of Letters Patent.

Patented Oct. 6, 1914.

Application filed November 29, 1913. Serial No. 803,817.

To all whom it may concern:

Be it known that I, DAVID J. WALLACE, of the United States Navy, a citizen of the United States, serving on U. S. S. *Panther*, 5 New York, in the county of New York and State of New York, have invented new and useful Improvements in Safety Gas-Burners, of which the following is a specification.

My invention relates to improvements in 10 gas burners, and one of its objects is the provision of a burner of this type with a novel means adapted to cut off the supply of gas to the tip on the accidental or positive extinguishing of the flame, whereby to avoid 15 those accidents which are usually incident to the extinguishing of the flame by the wind or the unintentional opening of the turning plug after extinguishing the flame.

A further object of the invention is the 20 provision of the burner with a gas igniting means adapted to be operated by the means controlling the flow of gas from the burner to the tip.

With the above and other objects in view, 25 the invention consists in the construction, combination, and arrangement of parts hereinafter described and claimed, and illustrated in the accompanying drawings, wherein—

Figure 1 is a view in side elevation of a 30 gas burner constructed in accordance with my invention, Fig. 2 is a sectional view taken on a plane extending vertically and centrally through the burner, the valve being shown in closed position, and Fig. 3 is a similar view, the valve being shown in opened position.

Referring to the drawings by reference numerals, 1 designates a gas bracket of the 40 usual construction and form, 2 being the turning plug, and 3 the threaded lug therefor.

My improved burner comprises a body 4 provided with a gas passage 4^a. The lower end of the body has threaded connection 45 with the stud 3, and the upper end thereof is provided with a tip 5. Projecting in opposite directions from the sides of the body 4 are alined extensions 6 and 7. The extensions 6 and 7 have cylindrical bores which 50 are arranged at right angles to the passage 4^a and which communicate with the passage through openings formed in the side walls of the body 4. The extension 6 forms a spring chamber, and the extension 7 a mercury chamber, and mounted in the chambers for movement across the passage 4^a is a solid

cylindrical valve 8. The valve 8 is provided with a port 9 which when the valve is in opened position registers with the passage 4^a and permits gas to flow to the tip 5. The 60 valve 8 is normally held in closed position, that is with the port 9 out of registration with the passage 4^a, by means of a coiled expansion spring 10 mounted in the chamber 6. The movement of the valve under the 65 influence of the spring 10 is limited by a pin 11 carried by the valve and traveling in a groove 12 which is formed in the upper wall of the chamber 6, said pin also preventing the rotation of the valve. A plug 13 closes 70 the outer end of the chamber 6 and is provided on its inner side with an inwardly extending tapered portion 14, which is adapted to limit the opening movement of the valve 8. The tension of the spring 10 may be reg- 75 ulated, and the opening movement of the valve 8 controlled, by adjusting the plug 13.

A reservoir 15 communicates with the chamber 7 and it and the chamber are full of mercury. The outer end of the chamber 7 80 is closed by a hollow plug 16 in which is mounted a piston 17. The rod 18 of the piston projects through the plug 16 and is provided with a manipulating head 19.

As before stated, the valve 8 is normally 85 held in closed position by the spring 10, cutting off the supply of gas to the tip 5. When it is desired to permit gas to flow to the tip 5, the piston 17 is moved inwardly through the medium of the manipulating 90 head 19. This movement of the piston 17 reduces the area of the mercury chamber 7, consequently forcing the valve 8 into opened position. A spring 20, which is carried by the plug 16, and which has a tension equal 95 to that of the spring 10, engages in a recess 21 in the piston rod 18 and holds the piston 17 inwardly. When the gas is ignited at the tip 5, the mercury in the chamber 7 expands, and as the valve 8 is held from movement to the right by means of the plug 100 extension 14, the pressure of the expanding mercury is directed against the piston 17, and when the pressure is sufficient to overcome the tension of the spring 20 the piston 105 is returned to its normal position. As long as the gas is burning at the tip 5 the valve 8 will be held in open position by the mercury, but as soon as the flame is extinguished, either through the medium of the 110 turning plug 2 or by accident, the mercury begins to condense, and when it is con-

densed the spring 10 forces the valve 8 into closed position, thereby cutting off the supply of gas to the tip 5. The plug 16 has threaded connection with the chamber 7, 5 and, therefore, should it be found necessary, it can be adjusted to increase or decrease the size of the chamber.

The igniting device comprises a friction member 22 secured to the upper wall of the 10 reservoir 15 and a piece of sparking material 23 carried by an arm 24. The arm 24 is secured to the manipulating head 19 of the piston 17 so that when the piston is moving inwardly to open the valve 8, the 15 sparking material 23 is moved over the friction member 22 creating a spark for igniting the gas as it issues from the tip 5. To prevent the rotation of the arm 24, whereby to maintain the sparking material 23 in proper 20 position with relation to the friction member 22, the arm 25 is secured at one end of the manipulating head 19 and has its opposite end disposed for movement in the groove 26 formed in the upper side of the mercury 25 chamber 7.

It should be apparent from the foregoing description taken in connection with the accompanying drawings, that I provide a gas burner which renders impossible those accidents usually incident to the extinguishing of a burner flame by the wind or the unintentional opening of the turning plug after extinguishing the flame. It should also be apparent that the safety gas burner is simple, durable, and efficient, that it may be manufactured and sold at a comparatively low cost, and that it may be readily and quickly applied to a gas bracket of any construction.

40 In the preferred embodiment of the invention, the body 4, chambers 6 and 7, and reservoir 15 will form a single casting.

Changes in the form, proportions and minor details of construction may be made 45 within the scope of the claims without departing from the spirit or sacrificing any of the advantages of the invention.

What I claim and desire to secure by Letters Patent is:—

50 1. A safety gas burner, comprising a body

having a gas passage, chambers arranged on opposite sides of the body and communicating with its passage, a ported valve mounted in the chambers for sliding movement across the passage, a spring in one of the chambers 55 to hold the valve normally closed, mercury in the other chamber, and a piston mounted in said other chamber.

2. A safety gas burner, comprising a body having a gas passage, chambers arranged on 60 opposite sides of the body and communicating with its passage, a ported valve mounted in the chambers for sliding movement across the passage, a spring arranged in one of the chambers to hold the valve normally closed, 65 mercury in the other chamber, a piston in said other chamber, and a spring adapted to engage the piston when in one position.

3. A safety gas burner, comprising a body having a gas passage, chambers arranged on 70 opposite sides of the body and communicating with its passage, a ported valve mounted in the chambers for sliding movement across the passage, a plug closing one of the chambers and provided with a stop, a spring 75 mounted between the plug and the valve, a plug closing the other chamber, mercury between said last named plug and the valve, a piston carried by said last named plug, and a spring adapted to engage said piston 80 when in one position.

4. A safety gas burner comprising a body having a gas passage, chambers arranged on opposite sides of the body and communicating with its passage, a ported valve 85 mounted in the chambers for sliding movement across the passage, means in one of the chambers to hold the valve normally closed, mercury in the other chamber, a piston mounted in said other chamber, and an 90 igniter carried by said piston, said igniter being actuated through the medium of said piston.

In testimony whereof I affix my signature in presence of two witnesses.

DAVID J. WALLACE.
